UNITED STATES PATENT OFFICE.

ABRAHAM HUGILL, OF SEAFORTH, ONTARIO, CANADA.

TOY WINDMILL.

Application filed May 18, 1925. Serial No. 31,189.

To all whom it may concern:

Be it known that I, ABRAHAM HUGILL, a subject of the King of Great Britain, and a resident of the town of Seaforth, in the county of Huron, in the Province of Ontario, Canada, have invented certain new and useful Improvements in Toy Windmills, of which the following is the specification.

My invention relates to improvements in toy windmills, and the object of the invention is to devise a toy of this type which will be ornamental and serve as a source of attraction and amusement to a very young child, and it consists essentially of the arrangement and construction of parts herein-after described in the following specification.

Fig. 1 is a perspective view of my toy windmill.

Fig. 2 is a sectional detail showing the journal support for the windmill fan members.

Fig. 3 is a detail showing the connection between the windmill tail and the main portion of the windmill.

Fig. 3^a is a face elevation of the parts shown in Figure 3.

In the drawings like characters of reference indicate corresponding parts in each figure.

1 and 2 indicate a pair of bar members set at right angles one to the other or cruciform.

3 is a body portion by which the rod members 1 and 2 are connected together at their point of intersection, the rod members passing through said body member and suitably secured therein. If desired, the opposite arms of the members 1 and 2 may be formed separately and screwed into the body 3 so that they may be detached from the body for the purpose of packing. The rod member 1 is provided at its upper end with a loop 4 by which it may be hung by a cord or other suitable means to any form of support.

5, 6, 7 and 8 are ornamental weights secured to the ends of the rod members 1 and 2, to give the device weight so as to keep it in a stable suspended position. If desired, the lower weight 7 may be removed and the lower portion of the bar member 1 used as a standard by which my windmill may be se-

cured by means of staples to a fence post or any other fixture.

9, 10, 11 and 12 are enlargements formed upon the rod members 1 and 2 intermediate between the central body portion 3 and each weight 5, 6, 7 and 8, or connected to the rod ends by such ends being screwed 60 thereto.

13 and 14 are stud pins which may be integral with the bosses 9, 10, 11 and 12, extending outwardly horizontally from each side of each boss, or may be separate therefrom and screwed into orifices therein.

Upon each stud member 13 is freely mounted a windmill member comprising a central body portion 15 mounted freely to revolve upon the stud pin 13 and from which extends a plurality of arms 16 carrying blades 17 set alternately at an angle one to the other so as to receive the wind pressure and cause each of the windmill members to revolve upon its respective stud pin 13. Similar windmill members 18 having central body portions are mounted upon the stud pins 14 at the opposite side of each boss 9, 10, 11 and 12, the blades being so set that the windmill members having the bodies 15 and 18 revolve in opposite directions.

The fan bodies 15 are secured on the stud pins 13 by split pins 19 or by other suitable means.

20 is a tail member. 20^a is a balancing spear. The tail member 20 is provided with a divided arm 21, and the balancing spear is provided with a divided arm 21^a.

The members of the divided arms 21 and 21^a extend at each side of the central body 3 and are provided with hook portions 22 which hook over the horizontal rod member 2 from opposite sides. The extremities of the hooks 22 are reversely turned, as indicated at 23 and 23^a, so as to engage outwardly extending pins 24 carried by the body 3. By this means the vane or tail member and the balancing spear are detachable for the purpose of storage or shipping. The balancing spear 20^a serves to balance the weight of the tail member 20.

By this means a swinging connection is formed between the tail member 20 and the spear 20^a and the frame so as to permit such tail and spear member being swung up adjacent to the main portion of the device for

the purpose of storing or shipping in compact form.

25 are stay wires connecting the rod members 1 and 2 together adjacent to each body 5 9, 10, 11 and 12.

The weights 5, 6, 7 and 8 may be secured to the ends of the rods 1 and 2 or may be connected to the enlargements 9, 10, 11 and 12 in a similar manner to the weight 20.

10 When in use my device is suspended from the ceiling or from any suitable support, and the wind serves to rotate each of the windmill members independently round their stud pins, and the blades of the windmill

15 may be variously coloured, so that as the windmills revolve they produce interweaving patterns which are very attractive to a child who is just beginning to observe surrounding objects.

20 A current of air may be provided by means of an electric fan or by any other means which will serve this purpose.

What I claim as my invention is:

1. A toy windmill comprising a central 25 body portion, arms radiating from such body portion, a loop formed on the upper end of a vertical extending arm to which suspension means are adapted to be attached, body members secured intermediately of the 30 length of each arm, stud pins extending from each side of said body members, a body rotatably mounted at each stud member, windmill arms radiating from the rotatably mounted member, and blades alternately reversely set upon each arm.

2. A toy windmill comprising a central body member, a vertical arm secured cen-

trally in such body member, a horizontal arm also secured centrally in such body member, a windmill member rotatably mounted upon each arm and at each side thereof and at each side of the central body member, and intermediately between such body member and the end of the arm.

3. A toy windmill comprising a central 45 body member, a vertical arm secured centrally in such body member, a horizontal arm also secured centrally in such body member, a windmill member rotatably mounted upon each arm and at each side 50 thereof and at each side of the central body member, and intermediately between such body member and the end of the arm, and a tail member swung upon the horizontal arm at each side of the central body member.

4. A toy windmill comprising a central body member, a vertical arm secured centrally in such body member, a horizontal arm also secured centrally in such body member, a windmill member rotatably 60 mounted upon each arm and at each side thereof and at each side of the central body member and intermediately between such body member and the end of the arm, a tail member provided at its inner end with a divided arm extending at each side of the central body member and each terminating in a hook extending over the horizontal arm having the extremity of each hook reversely set and a pin extending outward from each 65 side of the central body member to engage the reversely set portion of the corresponding hook.

ABRAHAM HUGILL.
